(57) CLAIM

The ornamental design for a hedgehog bag clip, as shown and described.

DESCRIPTION

FIG. 1 is a front elevational view of the hedgehog bag clip showing my design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a front perspective view thereof.

The broken lines shown in FIGS. 6 and 7 depict portions of the hedgehog bag clip that form no part of the claimed design.
